RAILWAY SIGNALING

George R. Pflasterer, Swissvale, Pa., assignor to
The Union Switch & Signal Company, Swiss-
vale, Pa., a corporation of Pennsylvania

Application August 14, 1936, Serial No. 95,998

16 Claims. (Cl. 246—41)

My invention relates to railway signaling systems wherein the signals normally indicate "stop" and are changed to indicate "proceed" or "caution" only when a train is approaching. 5 Specifically, my invention relates to apparatus, in a system of the type described, for automatically clearing the signals upon the approach of a train which apparatus does not require any additional line conductors over and above those 10 usually provided for the signal control circuits.

I will describe two forms of apparatus embodying my invention, and will then point out the novel features thereof in claims.

Figs. 1A and 1B of the accompanying drawings are diagrammatic views, which when placed end to end in the order named, illustrate one form of apparatus embodying my invention. Fig. 2 is a diagrammatic view illustrating a modification of a portion of the apparatus shown in 20 Fig. 1B and also embodying my invention.

Similar reference characters refer to similar parts in each of the several views.

Referring first to Figs. 1A and 1B, the reference characters 6 and 7 designate the rails of a 25 stretch of track over which traffic normally moves in the direction indicated by the arrows. The rails 6 and 7 are divided by insulated joints 8 into track sections W—X and X—Y. Each track section is divided into at least two sub-sections 1T, 2T, 3T, 4T, etc. Each sub-section is provided with a track battery 9 connected across the rails at one end of the sub-section and with a track relay, designated by the reference character TR with a prefix the same as the numerical 30 prefix of the associated sub-section, connected across the rails at the other end of the sub-section.

Each section is provided with a signal designated by a suitable distinguishing reference 40 character. Each signal, as here shown, comprises a "proceed" lamp G capable of displaying a green light, a "caution" lamp Y capable of displaying a yellow light, and a "stop" lamp R capable of displaying a red light.

45 For controlling the signals, each section is provided with a polarized direct current relay designated by the reference character HD with a prefix the same as the reference character of the associated signal. For governing the polarized 50 relays, each section is provided with a pair of line conductors each extending to the signal in advance and each including a front contact of each of the associated track relays. As will be explained more in detail hereinafter, the line conductors of each section are at times supplied with

alternating current as well as with direct current. The impedance of the polarized relays HD is of such value as will prevent the flow of alternating current in these relays.

5 Each section is provided with a source of direct current, here shown as a battery 13 with its terminals designated by the reference characters B and C.

The polarity of the current supplied to the line conductors for the section in the rear is governed 10 by the relay HD associated with the section in advance. That is, the line conductors for the section next in rear are supplied with direct current of normal polarity or reverse polarity according as the relay HD associated with the section in advance is energized or deenergized, respectively.

15 For supplying alternating current to the associated line conductors, each section is provided with a transformer, designated by the reference character N with a prefix the same as the reference character of the associated signal, and having a primary winding 15 and a secondary winding 16. Each secondary winding 16 is connected across the associated line conductors by a condenser designated by the reference character P with a prefix the same as the reference character 20 of the associated signal.

25 For supplying alternating current to the primary winding 15 of the transformers N, each section is provided with a device designated by the reference character A with a prefix the same as the reference character of the associated signal.

30 As here shown, each device A is an alternator of the vibrating reed type. Referring to alternator 10A, for example, an elastic member 17 is caused to vibrate between terminals 18 and 19 by a control winding 20. In the deenergized condition of alternator A, member 17 does not connect with either terminal 18 or 19 but does 35 connect with a terminal 21. When energy is supplied to the alternator, winding 20 will attract member 17 causing it to connect with terminal 19 and to move away from terminal 21, causing winding 20 to become deenergized. 40 Upon the deenergization of winding 20, the resilience of member 17 will cause it to move away from terminal 19 and to connect with terminal 18 as well as with terminal 21. The circuit for winding 20 being then again completed through 45 terminal 21, winding 20 will again attract member 17 causing the cycle of operation just described to be repeated. Winding 20 therefore 50 will be repeatedly energized and deenergized as long as energy is supplied to its control circuit. 55

When member 17 is in engagement with contact 18, the left-hand portion of primary winding 15 of transformer 10N will be energized in one direction whereas, when member 17 is in engagement with contact 19, the right-hand portion of primary winding 15 will be energized in the reverse direction. Alternating current therefore will be induced in secondary winding 16 of transformer 10N as long as alternator 10A is 10 operating.

For controlling the alternators A, as well as for controlling the lamp circuits of the associated signal and for connecting the associated relay HD to the corresponding line conductors, each 15 section is provided with an approach relay designated by the reference character AR with a prefix the same as the reference character of the associated signal. As here shown, each relay AR is normally deenergized and is connected in 20 series with the line circuit for the section next in rear. The pickup value of each relay AR is such that these relays will not become picked up on the value of the current required by the relay HD for the section next in rear but will only 25 become picked up if a path of comparatively low resistance is closed. For example, relay 11AR will not become picked up by the current supplied to relay 10HD from battery 13 at signal 11, but will only become picked up if either 30 track relay 2TR or 3TR is released so that either the path including shunt 22 or the path including shunt 23 is closed. In other words, the relays AR will become picked up only when the section 35 next in rear is occupied by a train. Connected across the winding of each relay AR is a resistor 24 which is provided to bypass the alternating current supplied to the line circuit controlling such relay so that the relays AR will not become picked up by alternating current.

40 Also for connecting the relays HD to the associated line conductors, each section is provided with an auxiliary approach relay designated by the reference character AX with a prefix the same as the reference character of the associated signal. Each relay AX receives energy from the line conductors for the section next in rear through an asymmetric unit and a transformer designated by the reference characters Q and M, respectively, each with a prefix the same 45 as the reference character of the associated signal. It will be readily apparent that the relays AX can be energized only when the line conductors for the section next in rear are supplied with alternating current.

50 The polarized relays HD control the signals in the usual manner. That is, when relay HD is deenergized (see signal 12), a readily traced circuit for the "stop" lamp R of that signal is established so that, when relay 12AR becomes 55 energized, the signal will display a red light to indicate "stop". When relay HD is energized in the reverse direction (see signal 11), a readily traced circuit for the "caution" lamp Y is established so that, when relay 11AR becomes energized, that signal will display a yellow light to indicate "approach next signal prepared to stop". When relay HD is energized in the normal direction (see signal 10), an easily traced circuit for the "proceed" lamp G is established 60 so that, when relay 10AR becomes energized, that signal will display a green light to indicate "proceed at normal speed".

65 As here shown, a train K is indicated diagrammatically in the section immediately to the left of location W so that track relay 1TR

is deenergized to cause the pickup of relay 10AR. The circuit for relay 10AR may be traced from terminal B of battery 13 at signal 10 through resistor 24 and relay 10AR in multiple, back point of contact 26 of relay 10HD, back point 5 of contact 27 of relay 1TR, shunt 28, back point of contact 29 of relay 1TR, primary winding 30 of transformer 10M, and back point of contact 31 of relay 10HD to terminal C of battery 13.

Since relay 10AR is energized, relay 10HD is 10 connected to the line conductors for section W-X by front contact 32 of relay 10AR, and a circuit is closed to cause the operation of alternator 10A over front contact 33 of relay 10AR.

15 Since secondary winding 16 of transformer 10N is energized by alternating current, the line circuit for section W-X is supplied with alternating current so that primary winding 34 of transformer 11M is energized. The energization of primary winding 34 induces current in secondary winding 35 so that relay 11AX is energized through asymmetric unit 11Q. The circuit for primary winding 34 of transformer 11M may be traced from one terminal of secondary winding 16 of transformer 10N, through condenser 10P, front point of contact 36 of relay 2TR, primary winding 34 of transformer 11M, front point of contact 39 of relay 11HD, resistor 24, battery 13 at signal 11, front point of contact 38 of relay 11HD, front contact 40 of relay 3TR, front contact 41 of relay 2TR to the other terminal of transformer 10N.

20 Since relay 11AX is energized, its front contact 42 is closed to connect relay 11HD with the line conductors for section X-Y so that relay 11HD is energized in the reverse direction. The circuit for relay 11HD may be traced from terminal B of battery 13 at signal 12 through resistor 24 and relay 12AR in multiple, back point of contact 43 of relay 12HD, front point of contact 44 of relay 5TR, front point of contact 45 of relay 4TR, relay 11HD, front point of contact 42 of relay 11AX, front point of contact 46 of relay 4TR, front point of contact 47 of relay 5TR, primary winding 34 of transformer 12M, and back point of contact 48 of relay 12HD to terminal C of battery 13 at signal 12.

25 Since relay 11HD is energized, relay 10HD is 30 energized in the normal direction so that signal 10 is caused to display the normal proceed indication. The circuit for relay 10HD may be traced from terminal B of battery 13 at signal 11 through resistor 24 and relay 11AR in multiple, front point of contact 39 of relay 11HD, primary winding 34 of transformer 11M, front point of contact 37 of relay 3TR, front point of contact 36 of relay 2TR, front contact 32 of relay 10AR, relay 10HD, front point of contact 41 of relay 2TR, front point of contact 40 of relay 3TR, and front point of contact 38 of relay 11HD to terminal C of battery 13 at signal 11.

35 The polarized relays HD are preferably of the retained neutral type so that a momentary energization of the red lamp will be avoided during periods of change of polarity. For example, when front contact 32 of relay 10AR becomes closed, relay 10HD will be momentarily energized in the reverse direction until such time as the relay 11HD becomes energized. If the retained neutral feature, however, is provided, the back neutral contacts of relay 10HD will not become momentarily closed to cause a flash of 40

the red lamp when the energization of the relay 10HD is changed from the reverse direction to the normal direction by the picking up of relay 11HD.

5 The relays AR are provided with a slow releasing characteristic so that the circuit for the associated relay HD will not become opened when the neutral contacts of such associated relay HD are changed from a released to a picked up condition. For example, when relay 10HD becomes energized, the circuit for relay 10AR will be momentarily opened during the time contacts 26 and 34 of relay 10HD are moving between their back points and their front points. Due 10 to the slow releasing characteristic, however, relay 10AR will remain in its picked up condition during this period so that the energization of relay 10HD will not be disturbed. The relays AX are provided with a slow releasing characteristic 15 so that the line circuit for the control of the associated relay HD will remain closed during the periods when the latter relay is being transferred to control by the associated relay AR. For example, when the train K enters section 20 W—X, relay 2TR will become released so that energy will be disconnected from relay 11AX and so that the relay 11AR will become picked up. The slow releasing feature of relay 11AX insures that the line circuit for the control of relay 25 11HD will remain closed until such time as relay 11AR becomes picked up. Relay 11HD, therefore, remains in its energized condition.

Referring now to Fig. 2, I have shown herein one signal and associated apparatus which, 30 when included in a system with wires 50 and 51 at the right connected to wires 52 and 53, respectively, at the left, will provide two-block, three-indication, signaling similar to that described for the apparatus shown in Figs. 1A and 1B.

40 The principal difference between the system illustrated in Fig. 2 and that illustrated in Figs. 1A and 1B is that the relay AR in Fig. 2 is normally energized instead of normally deenergized. In order to provide a closed circuit for the normal energization of the relay AR, a resistor J has been substituted for the condenser P between the secondary winding 16 of the transformer N and the associated line circuit.

When the rear section becomes occupied by a 50 train, the releasing of the track relay opens the circuit for the relay AR so that its back contacts 54 and 55 become closed. The closing of back contact 54 connects relay HD to its line circuit and the closing of back contact 55 initiates the 55 operation of alternator A and energizes one of the signal lamp circuits depending upon the condition of relay HD.

Otherwise the apparatus operates in a manner similar to that described for the apparatus shown 60 in Figs. 1A and 1B and it is considered, therefore, unnecessary to provide further detailed explanation of the operation of the apparatus shown in Fig. 2.

65 From the foregoing description of the apparatus embodying my invention, it will be seen that I have provided simple and reliable normal danger signal systems wherein the signals normally indicate "stop" and are caused to indicate "caution" or "proceed" only when a train is approaching. Furthermore, my systems do not require the use of additional line conductors over and above those usually provided for the signal control circuits, and the systems are unusually economical in current consumption since normally, that is, when

no train is approaching, only a relatively small amount of energy is required.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a forward and a rear section as well as an intermediate section of railway track, an approach relay normally in one condition but operable to a different condition when the rear section becomes occupied by a train, 10 an auxiliary relay normally in one condition but operable to a different condition when said approach relay is in its different condition, a signal control relay for the forward section and a signal control relay for the intermediate section, a circuit 15 for supplying energy to the signal control relay for the forward section including a contact which is closed when said auxiliary relay is in its different condition, and a circuit for supplying energy to the signal control relay for the intermediate section governed by the signal control relay for the forward section and including a contact which is closed when said approach relay is in its different condition.

2. In combination, a forward and a rear section as well as an intermediate section of railway track, an approach relay normally in one condition but operable to a different condition when the rear section becomes occupied by a train, an auxiliary relay normally in one condition but operable to a different condition when said approach relay is in its different condition, a first signal control relay for the forward section and a second signal control relay for the intermediate section, means for energizing said first 30 signal control relay when said auxiliary relay is in its different condition provided the forward section is then unoccupied, and means for reversibly energizing said second signal control relay in accordance with the condition of said first 35 relay when said approach relay is in its different condition provided the intermediate section is 40 then unoccupied.

3. In combination, a forward and a rear section as well as an intermediate section of railway track, an approach relay normally in one condition but operable to a different condition when the rear section becomes occupied by a train, an auxiliary relay normally in one condition but operable to a different condition when said approach relay is in its different condition, a pole 50 changer for the forward section governed by traffic conditions in that section and by said auxiliary relay, and traffic governing means for the intermediate section governed by said pole 55 changer and by said approach relay.

4. In combination, a forward and a rear section as well as an intermediate section of railway track, an approach relay normally in one condition but operable to a different condition 65 when the rear section becomes occupied by a train, an auxiliary relay normally in one condition but operable to a different condition when said approach relay is in its different condition, a pole changer for the forward section governed 70 by traffic conditions in that section and by said auxiliary relay, a signal control relay governed by said pole changer and by said approach relay, and a signal for the intermediate section governed by said signal control relay.

5. In combination, a forward and a rear section as well as an intermediate section of railway track, an approach relay normally in one condition but operable to a different condition when the rear section becomes occupied by a train, an auxiliary relay normally in one condition but operable to a different condition when said approach relay is in its different condition, a first relay for the forward section and a second relay for the intermediate section, a first circuit for said first relay and a second circuit for said second relay, means for closing said first circuit when said auxiliary relay is in its different condition provided said forward section is then unoccupied, means for supplying said second circuit with current in one direction or another according as said first relay is energized or de-energized, respectively, and means for closing said second circuit when said approach relay is in its different condition provided the intermediate section is then unoccupied.

6. In combination, a forward and a rear as well as an intermediate section of railway track, a normally deenergized approach relay which becomes energized when the rear section is occupied by a train, a normally deenergized auxiliary relay which becomes energized when said approach relay is energized, a first relay for the forward section and a second relay for the intermediate section, a circuit for supplying energy to said first relay including a front contact of said auxiliary relay, and a circuit for supplying energy to said second relay governed by said first relay and including a front contact of said approach relay.

7. In combination, a forward and a rear as well as an intermediate section of railway track, a normally energized approach relay which becomes deenergized when the rear section is occupied by a train, a normally deenergized auxiliary relay which becomes energized when said approach relay is deenergized, a first relay for the forward section and a second relay for the intermediate section, a circuit for supplying energy to said first relay including a front contact of said auxiliary relay, and a circuit for supplying energy to said second relay governed by said first relay and including a back contact of said approach relay.

8. In combination, a forward and a rear as well as an intermediate section of railway track each provided with a track circuit including a track relay, a normally deenergized approach relay, means including a back contact of the track relay for the rear section for energizing said approach relay, a normally deenergized auxiliary relay, means including a front contact of said approach relay for energizing said auxiliary relay, a first relay for the forward section and a second relay for the intermediate section, a circuit for said first relay including a front contact of said auxiliary relay and a front contact of the track relay for the forward section, and a circuit for said second relay governed by said first relay and including a front contact of said approach relay and a front contact of the track relay for the intermediate section.

9. In combination, a forward and a rear as well as an intermediate section of railway track, an approach relay normally in one condition but operable to a different condition when said rear section becomes occupied, a signal control relay, a circuit for said signal control relay governed by traffic conditions in the intermediate section and including a pair of conductors as well as a

contact which is closed when said approach relay is in its different condition, a normally de-energized auxiliary relay, means including said pair of conductors for energizing said auxiliary relay when said approach relay is in its different condition, a pole changing relay for governing the direction of energization of said pair of conductors, and means for governing said pole changing relay in accordance with traffic conditions in the forward section effective when said auxiliary relay is energized.

10. In combination, a forward and a rear as well as an intermediate section of railway track, an approach relay normally in one condition but operable to a different condition when said rear section becomes occupied, a signal control relay for the intermediate section and responsive only to current of a particular character, a pair of line conductors extending through the intermediate section and connected to said signal control relay when said approach relay is in its different condition, means including a pole changer for the forward section for supplying said pair of conductors with current of said particular character in one direction or the other, a normally deenergized auxiliary relay, means responsive only to current of a different character connecting said auxiliary relay to said pair of conductors, means for supplying said pair of conductors with current of said different character when said approach relay is in its different condition, and means effective when said auxiliary relay is energized to place said pole changer under control by traffic conditions in the forward section.

11. In combination, a forward and a rear section as well as an intermediate section of railway track, a pair of conductors for the intermediate section, a direct current signal control relay for the intermediate section, an approach relay normally in one condition but operable to a different condition when the rear section becomes occupied by a train, means effective to connect said signal control relay to said pair of conductors and also to supply said pair of conductors with alternating current when said approach relay is in its different condition, a direct current auxiliary relay receiving energy from said pair of conductors through an asymmetric unit, and means effective when said auxiliary relay is energized to supply said pair of conductors with direct current of one polarity or the other according to traffic conditions in the forward section.

12. In combination, a forward and a rear section, as well as an intermediate section of railway track, a pair of conductors for the intermediate section, a direct current signal control relay for the intermediate section, an approach relay normally in one condition but operable to a different condition when the rear section becomes occupied by a train, means effective to connect said signal control relay to said pair of conductors when said approach relay is in its different condition, means including an alternator effective to supply said pair of conductors with alternating current when said approach relay is in its different condition, a direct current auxiliary relay receiving energy from said pair of conductors through an asymmetric unit, and means effective when said auxiliary relay is energized to supply said pair of conductors with direct current in one direction or the other according to traffic conditions in the forward section.

13. In combination, a forward and a rear section as well as an intermediate section of railway track, a pair of conductors for the intermediate section, a direct current signal control relay for the intermediate section, an approach relay normally in one condition but operable to a different condition when the rear section becomes occupied by a train, means effective to connect said signal control relay to said pair of conductors when said approach relay is in its different condition, an alternator capable of supplying alternating current to said pair of conductors, means effective to cause the operation of said alternator when said approach relay is in its different condition, a pole changer connected between a source of direct current and said pair of conductors, and means responsive only to alternating current effective when energized to place said pole changer under control by traffic conditions in the forward section.

14. In combination, a forward and a rear section as well as an intermediate section of railway track, a pair of conductors for the intermediate section, a direct current signal control relay for the intermediate section, an approach relay normally in one condition but operable to a different condition when the rear section becomes occupied by a train, means effective to connect said signal control relay to said pair of conductors when said approach relay is in its different condition, an alternator capable of supplying alternating current to said pair of conductors, a circuit for energizing said alternator including a contact which is closed when said approach relay is in its different condition, a pole changer connected between a source of direct current and said pair of conductors, and means responsive only to alternating current effective when energized to place said pole changer under control by traffic conditions in the forward section.

15. In combination, a stretch of railway track

divided into sections, a signal for each section, a signal control circuit for each section for supplying energy to the associated signal, an approach relay for each section normally in one condition but operable to a different condition when the section next in rear of the associated section becomes occupied by a train, means for each section effective to connect its signal with the corresponding control circuit when the associated approach relay is in its different condition, an auxiliary relay for each section normally in one condition but operable to a different condition when the approach relay for the section next in rear is in its different condition, and means for each section effective to connect its signal with the corresponding control circuit when the associated auxiliary relay is in its different condition.

16. In combination, a stretch of railway track divided into sections, a signal control relay for each section, a signal control circuit for each section for supplying energy to the associated signal control relay in one direction or the other according as the signal control relay for the section next in advance is energized or deener- 25 gized, an approach relay for each section normally in one condition but operable to a different condition when the section next in rear becomes occupied by a train, means for each section effective to connect its signal control relay to 30 the corresponding signal control circuit when the associated approach relay is in its different condition, an auxiliary relay for each section normally in one condition but operable to a different condition when the approach relay for the section next in rear is in its different condition, and means for each section effective to 35 connect its signal control relay with the corresponding control circuit when the associated aux- 40 iliary relay is in its different condition.

GEORGE R. PFLASTERER.
